UNITED STATES PATENT OFFICE

CHARLES J. GUTBERLET, OF PHILADELPHIA, PENNSYLVANIA

MACHINE FOR TREATING PYRALINE ENVELOPE BLANKS

Application filed July 8, 1927. Serial No. 204,403.

The present device prepares the blanks for pyraline envelopes for bending into the completed form. Such a machine has to give an even heating readily controlled, to the lines 5 of flexion of the blank when it is bent to form the envelope. A lesser heat has to be given to its folded over flaps at places not directly at the fold, and sufficient adjustability must be given so that envelopes of 10 different sizes and shapes may have the blanks treated by it.

Fig. 1 is a front elevation of the machine. Fig. 2 is a plan view of same. Fig. 3 is a side elevation of the same. Fig. 4 is a diagram 15 showing the course of the electric current through part of the machine. Fig. 5 is a fragmentary view on an enlarged scale of a portion of the top block viewed from beneath, the movable hot plate being shown as positioned near the opposite stationary hot plate. Fig. 6 is a section on line 6-6 of Fig. 5. Fig. 7 is a fragmentary view of the adjustable hot plate.

The machine has a hot plate block and 25 the bed plate having the guides for the blanks. The parts are separated and closed by suitable mechanism, which is automatic for the reason among others, that the closed period is advantageously of a constant duration. A rheostat 21 is provided to regulate the quantity 30 of electric current passing through the coils of the hot plates. The hot plate block is movable and the bed stationary. By this arrangement the upper jaw preferably carries the hot 35 plates and the lower jaw the guides for the blanks. Also, by this arrangement the duration of contact of the hot plates with the pyraline is made independent of any irregularity in manual feeding.

40 Describing now in detail the best construction of my device of which I am at present aware; A stationary bed plate, 3, carrying the pyraline blank while being treated, is provided with the guides, 1, and 2 and the stop, 45 11. The guide, 2, is adjustable conveniently by being provided with the projecting adjusters 39 that are positioned by the clamps 38. The block, 4, that carries the hot plates is hinged to the bed plate at the ends of the 50 arms, 30, 30, and the hot plates rest yield-

ingly upon the bed plate, 3, or if the blank has been fed into the machine, upon the blank. The block, 4, and its hot plates are lifted by the cams, 7, 7, acting on the cam bearings 10 which are fastened to the connections 6, 6, 55 attached to the block, 4. By rotating these cams at a constant speed the duration of the contact between the hot plates and the blanks is made practically equal in time for every blank. Any variation being that if one of the blanks is thicker than another the thicker blank will have a slightly longer contact. The cams can be carried by the ears, 80, 80, 60 projecting from a standard, 5, that also carries a rheostat, 21, having the movable contact, 31 and the fixed contacts, 41.

A means by which the cams, 7, 7, are driven at constant speed is illustrated in Figures 1, 2, and 3. The cams are mounted on shafts driven by the gear wheels, 27, 27, that are, in turn, driven by the gear wheel, 28, which is placed on the same shaft as the pulley, 29, which is driven by the belt, 56.

The hot plates, 8, 18, and 9 are carried by 75 the block, 4. The hot plates, 8, and 18 are usually fixed and fit with the guides, 1, and stop, 11 but the hot plate, 9, is adjustable to fit with the guide 2. The hot plates, 8, and 18, have the ridges, 39, 39, which register with the lines on which the blanks are folded; and lie away from the outside edges of the hot plates. The movable hot plate, 9, has similarly the ridge, 49. So positioning these ridges is because the flaps of the blank, intended to be turned over, will lie outside the 80 folding lines of the blank.

85 A suitable construction of the hot plates is shown in Figs. 4, 5, and 6. The heating coils, as 53, 91 and 54, are placed inside a casing such as that formed of the plates, 94, 92 and 93, (see particularly Fig. 6). The electrical connections between the heating coil of the movable hot plate and the rest of the circuit is very conveniently made by means of a strip, 50, of a conducting material that contacts with a wire, 96, passing through the insulation, 95.

90 As the present machine is intended to operate with a substantially fixed time of contact between the hot plate and the pyraline, 100

varying the heating of the hot plates to accommodate them to softening the pyraline when of different grades and thickness, is often very important. For this purpose the inclusion of a rheostat or similar device in the heating circuit is very advantageous. An illustrative diagram of the course of the electric current through the heaters for the hot plates is shown in Fig. 4. 60 is a source of electrical energy 67 a conductor leading to the movable arm 31 of the rheostat 21 and 91, 53 and 54 a series of heating coils. In the form of my invented device which I find best in practice the current (see Fig. 5) is carried from the binding post 62, to the coils 52 of the heater for the hot plate 18, and to the bar 50 which latter is in electrical connection with the heating coil 91 through the conductor 96 which passes through the insulation 95 insulating the side plates 93 and 92 from the conductor 50. The grounding of the circuits may be accomplished very conveniently on the machine itself. The course of the current through the coils 53, 54 and 91 is illustrated diagrammatically in Fig. 4 where 60 is a source of electrical energy that is grounded through the conductor 68 to the ground 55. The other pole of the generator 61 is connected by the conductor 67 and the movable arm 31 and the fixed arm 41 of the rheostat 21 and the conductor 61 with the coils 53, 54 and through the conductor 50 with the coil 91. The current, after traversing these coils, passes through the conductor 75 to the ground 76. Fig. 3 shows part of the course of a current through the machine. The conductor 64 connects electrically the rheostat 21 and the coils of the hot plates 8, 18, and 91, and the conductor 65 connects the rheostat 21 with a ground 550.

The machine is operated by passing an electric current through the hot plate coils, and causing the hot plate block to be lifted, and lowered so that it will rest on the blank on the bed. The parts of the blank with which the ridges, 39, and 49, contact will be more heated than the parts lying beneath the other parts of the hot plates. The heat of the plates and the time of contact with the blanks determine the extent of the softening of the substance of the pyraline and its flexibility. Within reasonable limits in practice I make the period of reciprocating movement of the hot plate block constant and use the rheostat to regulate the amount of current flowing through the coils, and consequently their temperature.

My invention is not limited to the particular form of press mechanism employed otherwise than that the hot plate block is allowed to descend yieldingly upon the bed and to rest the hot plates on the blank without producing positive pressure thereon, nor is it limited by the particular form of the electric heaters, nor by the particular means for vary-

ing the current through them; and generally I do not limit myself otherwise than by the claims attached hereto.

I claim:

1. In a machine for softening pyraline envelope blanks along the lines of the intended folds to be made therein, having a bed and a hot plate block positioned above and movable towards and away from said bed, and actuated toward said bed, the combination comprising automatic lifting mechanism positioned to lift positively the hot plate block, and to allow it to descend yieldingly upon the bed, alternately, hot plates having projecting ridges corresponding to the lines of the folds desired to be made in said blanks and electrical heaters for said hot plates the said automatic lifting mechanism having provisions allowing the hot plates to descend until stopped by contact with the blanks and pause before being again lifted. 70 75 80 85

2. In a machine for softening pyraline envelope blanks along the lines of the folds intended to be made therein, having a bed and a hot plate block positioned above and movable towards and away from said bed, and actuated yieldingly toward said bed, the combination comprising automatic lifting mechanism alternatively lifting positively and allowing to descend yieldingly said hot plate block upon the bed, hot plates positioned upon said block and having ridges elevated above the rest of the surface of the block corresponding to the lines of the folds intended to be made in the blank, electrical heaters for said blanks and means for varying the current passing through said heaters thereby varying grades and thicknesses of pyraline may be treated without changing the speed of the said automatic mechanism. 90 95 100 105

3. In a machine for softening pyraline envelope blanks, along the lines of the folds intended to be made therein, a bed and a hot plate block positioned above and movable toward and away from said bed and means for yieldingly actuating the hot plate block toward the bed, the combination with the hot plate block of electrically heated, hot plates secured to said hot plate block each plate having a longitudinal ridge extending the length of said hot plate, said hot plates being arranged upon said block so that the said ridges will contact with the blank along the line of the folds intended to be made in said blank. 110 115 120 125

4. The device as defined in claim 3 wherein one of the hot plates is adjustable along said block toward and away from the other hot plates.

5. In a machine for treating pyraline envelope blanks to soften the same along the lines of the folds intended to be made in said blanks, the combination comprising a set of elongated electrically heated hot plates, each plate having a longitudinal ridge projecting 120 125

beyond the general level of such plate, means
for bringing yieldingly the said ridges in con-
tact with the said blank along the lines of the
folds intended to be made therein, and means
for controlling the temperature of said plates
by varying the electric current.

6. The device as defined in claim 5 wherein
one of the said hot plates is adjustable with
reference to the other.
